UNITED STATES PATENT OFFICE.

MICHAEL PEKICH, OF PITTSBURGH, PENNSYLVANIA.

STEAM LOCOMOTIVE.

Application filed June 30, 1927. Serial No. 202,572.

My invention relates to improvements in steam locomotives and feed-water heaters therefor, although the invention is applicable also to steam engines of other types.

5 Broadly stated, my invention comprises means for utilizing exhaust steam for effecting a preliminary heating of the feed water, such exhaust steam being so directed that it will not only facilitate the draft through 10 the fire box, but will be muffled to a considerable extent, thereby reducing the exhaust sound ordinarily present in locomotives and other steam engines.

My invention has for one of its objects the 15 provision of an improved means for heating feed water.

Another object of my invention is to deaden the sound of the locomotive exhaust and to reduce the volume of smoke and exhaust 20 gases that ordinarily issue from the stack.

One form which my invention may take is shown in the accompanying drawing, wherein Figure 1 is a longitudinal sectional view of a portion of the locomotive, and Fig. 2 is a view taken on the line II—II of Fig. 1.

The locomotive is of somewhat the usual type, being provided with a fire box 3, a 30 smoke box 4 and a series of arch tubes 5 that are connected to the water spaces and the front and rear of the fire box in the usual manner. A feed water pipe 6 is connected to an injector and a source of supply in any 35 usual manner and leads into a conduit 7 that is formed by concentric tubes 8 and 9. Packing rings 10 and 11 are provided at the front and rear ends respectively of the tubes 8 and 9, so as to close the ends of the space 7 between such tubes.

A steam exhaust pipe 12, which is connected to the locomotive cylinders has connection with the interior of the tube 9 so 40 that steam will be directed through said tube into a chamber 13, the forward wall of which is provided with perforations 14 that direct the exhaust steam forwardly through the fire tubes of the locomotive and thence out the stack. The sound of the exhaust is thereby deadened, and the jets of steam issuing 45 from the perforations 14 facilitates the draft. When water is being admitted through the injector pipe 6, it will pass through the space 7 and through passages 15

chamber 13. From the compartment 16, the water will flow through pipes 17 and 18 that have connection with the fire tubes 5, there being as many pipes 17 and 18 as desired, depending somewhat upon the size of the 60 compartment 16.

As the water flows through the passage 7, it will be heated by the exhaust steam and a saving in fuel thereby effected. The provision of pipes 17 and 18 at different levels 65 permits of circulation of water through the compartment 16 when no water is flowing into the locomotive through the pipe 6, thus preventing over-heating of such compartment.

The arrangement of the tubes 8 and 9 and the chamber 13 is such that the apparatus can be installed in existing types of locomotives, without materially altering the structure of the locomotives, by reason of the 75 fact that the said tubes can be inserted in the space normally occupied by some of the fire tubes, and the chamber 13 can be placed in the space usually found above the arch, and can be conveniently removed and applied. 80

At the upper end of the smoke box 4, I provide a fan 20 driven from any suitable source of power (not shown), as a steam turbine, that serves to draw the heavier particles from the exhaust gases and direct them, 85 through a conduit 21 to the space 22 beneath the grates. The amount of smoke and solids deflected by the fan 20 from the stack is greater by reason of the fact that the exhaust steam tends to precipitate or render heavier 90 the solid or semi-solid particles in the exhaust gases, thus reducing the amount of smoke issuing from the stack and effecting a saving in fuel, by causing the deflected material to be passed through the fire bed. 95

In case it is not desired to pass the smoke and gases from the pipe 21 through the grate, such gases may be deflected by a three-way valve 21^a of any suitable form which may be operated by a pull rod or link 23 from the locomotive cab (not shown), so that the smoke and gases will be by-passed through a pipe 24 that leads to the front end of the smoke box where it will be at least partially consumed. 100

From all of the foregoing, it will be seen that I effect a saving in fuel, through heating of the feed water with the normally wasted exhaust steam, and by consuming products

through the stack, in addition to deadening the sound of the exhaust and eliminating smoke to a large degree.

I claim as my invention:—

- 5 1. The combination with a locomotive, of a feed water heater therefor, comprising a steam exhaust pipe leading rearwardly through the boiler and having openings at its rear end to permit exhaust to the locomotive stack, a passage surrounding said pipe, a water inlet pipe connected to said passage at one end, and a connection between said passage and the water space in the boiler at its other end.
- 10 2. The combination with a locomotive having a fire box, fire tubes and a stack, of a steam exhaust pipe leading rearwardly from a point adjacent to the front end of said tubes to the fire box, a passage-way surrounding said pipe, means for directing feed water into one end of said passageway, and means permitting flow of said water from the other end of said passage-way.
- 15 3. The combination with a locomotive having a fire box, fire tubes, and a stack, of a steam exhaust pipe leading rearwardly from a point adjacent to the front end of said tubes to the fire box, a passage-way surrounding said pipe, means for directing feed water into one end of said passageway, means permitting flow of said water from the other end of said passageway, and means for directing the exhaust steam forwardly from said fire box, through the fire tubes.
- 20 4. The combination with a locomotive having fire tubes, a fire box, and arch tubes, of a steam exhaust pipe leading rearwardly from the front end of said tubes, a chamber connected to the rear end of said pipe and connected to the rear end of said pipe and
- 25

having forwardly extending perforations, a passageway surrounding said pipe, a compartment surrounding said chamber, a water inlet pipe connected to the forward end of the passageway, a connection between the rear end of the passage-way and said compartment, and a connection between said compartment and the water space in the boiler.

5. The combination with a locomotive having fire tubes, a fire box, and arch tubes, of a steam exhaust pipe leading rearwardly from the front end of said tubes, a chamber connected to the rear end of said pipe and having forwardly extending perforations, a passageway surrounding said pipe, a compartment surrounding said chamber, a water inlet pipe connected to the forward end of the passageway, a connection between the rear end of the passageway and said compartment and connections between said compartment and the arch tubes.

6. The combination with a locomotive having fire tubes, a fire box, and arch tubes, of a steam exhaust pipe leading rearwardly from the front end of said tubes, a chamber connected to the rear end of said pipe and having forwardly extending perforations, a passageway surrounding said pipe, a compartment surrounding said chamber, a water inlet pipe connected to the forward end of the passageway, a connection between the rear end of the passageway and said compartment, and a connection between the upper and lower portions of said compartment and the water space in the boiler.

In testimony whereof I, the said MICHAEL PEKICH, have hereunto set my hand.

MICHAEL PEKICH.
